UNITED STATES PATENT OFFICE

2,464,085

TOILET BRUSH CONTAINER

Ethel M. Hess, Brook, Ind.

Application April 27, 1946, Serial No. 665,540

1 Claim. (Cl. 206—15.1)

1

The invention pertains to a toilet brush holder and more specifically has reference to an enclosure for conveniently supporting and concealing a toilet utensil.

The primary objects of the invention are to provide a container which is particularly adapted to receive and support in readily accessible manner a toilet brush; to provide a means for receiving the drippings from such a brush after use which means may be easily removed without disturbing the brush or its container; and to effect a concealment of such a brush.

Ancillary objects of the invention are to provide an arrangement according to the foregoing objects which is compact, unobtrusive and inexpensive.

These, together with numerous other objects of the invention which will later become apparent as the following description proceeds, are attained by my device, one embodiment of which has been illustrated by way of example only in the attached drawings, wherein:

Figure 1 is a side elevation, partly in section, showing a preferred embodiment of the device;

Figure 2 is a top plan view of Figure 1;

Figure 3 is a rear elevation, parts being broken away, illustrating the manner of using the device; and

Figure 4 is a horizontal sectional view taken substantially upon the line 4—4 of Figure 1.

Referring now specifically to the drawings, the invention which may be formed of various suitable materials, is indicated generally at 10, and comprises a circular base 12 upon which rises a semi-cylindrical screen or shield 14, having a corresponding semi-circular top 16. Across the back end of the upper portion of the screen 14, and depending from the top 16 is a strip 18 which serves to reinforce the screen and to support a hook member 20, which as shown in Figure 4 has a rear portion or leg 22 secured to the back of strip 18 while a right angularly disposed extremity 24 extends rearwardly through the strip. The portion 24 provides a support for detachably receiving an eye 26 secured to the handle 28 of a toilet bowl brush 30. The base 12

2

is provided around its exposed circumference with an upstanding rim 32 which retains and encloses a container 34 which receives the drippings from the brush.

From the foregoing explanation, the operation of the device will be apparent. The container 10 is situated in any convenient location, preferably in a bath room, with the screen 14 to the front and concealing the brush 30 hanging thereon, as well as the drip container 34, from view. When the services of the brush 30 are required, the handle 28 may be readily detached from the container. The drip container 34 may be readily removed from the base 12, for emptying, without disturbing the rest of the device.

It is to be understood that I do not restrict myself to the exact construction disclosed, but may avail myself of various suitable modifications of the invention falling properly within the scope 20 of the appended claim.

I claim as my invention:

A toilet brush container comprising a semi-cylindrical screen, a semi-circular top for said screen having its edges conterminous with the upper edges of the screen, a reinforcing member across the open side of said screen along the straight side of said top and a brush supporting hook secured to said reinforcing member, and a circular base member for said screen, a rim around said base member for retaining and surrounding a drip pan below said brush.

ETHEL M. HESS.
